(57) **CLAIM**

The ornamental design for the inflator, as shown and described.

DESCRIPTION

FIG. 1 is an isometric view of the inflator.

FIG. 2 is a front view of the inflator.

FIG. 3 is a rear view of the inflator.

FIG. 4 is a side view of the inflator.

FIG. 5 is an opposite side view of the inflator.

FIG. 6 is a top view of the inflator; and,

FIG. 7 is a bottom view of the inflator.

The broken lines in the drawings depict portions of the inflator that form no part of the claimed design.
